[57] CLAIM

The ornamental design for a leg holster, as shown and described.

DESCRIPTION

FIG. 1 is a front perspective view of a leg holster showing my new design, the dotted line showing being for illustrative purposes only.

FIG. 2 is an upper perspective view of the leg holster.

FIG. 3 is an opposing perspective view of the leg holster as shown in FIG. 2.

FIG. 4 is a top view of the leg holster.
